United States Patent Office

Des. 195,645
Patented July 9, 1963

195,645

TORQUE TESTER

Edward T. Able, Denver, Colo., assignor to B. K. Sweeney
Mfg. Co., Denver, Colo., a corporation of Colorado

Filed Aug. 20, 1962, Ser. No. 71,419

Term of patent 14 years

(Cl. D52—6)

FIG. 1

FIG. 2

FIG. 3

FIG. 4

FIG. 1 is a front elevational view of a torque tester, showing my new design;

FIG. 2 is a side elevational view thereof;

FIG. 3 is a top plan view thereof; and

FIG. 4 is an isometric view thereof.

I claim:

The ornamental design for a torque tester, as shown.
